UNITED STATES PATENT OFFICE.

ROBERT E. HENRY, OF PITTSBURGH, PENNSYLVANIA.

COVERING FOR BATHTUBS AND THE LIKE.

Application filed October 9, 1925. Serial No. 61,456.

My invention relates to protective coverings for bath tubs, lavatories and similar porcelain and enameled plumbing goods.

Considerable difficulty has heretofore been experienced in suitably protecting plumbing fixtures, such as bath tubs, wash bowls and the like, during shipment and installation. The highly finished surfaces of these articles many times become scratched during handling and are also damaged during installation, by reason of plaster, mud and cement falling upon the articles and scratching the surface when being removed therefrom, through workmen dropping their tools into the tubs or standing in them, and from various other causes. Even slight injury reduces the tub to the rank of second quality, and in many cases causes rejection thereof by the purchaser, with the consequent expense of returning the same to the factory and the shipment of a replacement which may in turn also become damaged.

My invention has for its object the provision of a temporary protective covering for bath tubs and the like, of such form and material that the tub will be adequately protected during shipment and installation, and which will not readily become accidentally detached or torn from the tub.

I also avoid the necessity of applying adhesives to the polished surfaces of tubs, for holding a covering in place.

Some of the forms which my invention may take are shown in the accompanying drawing, wherein Fig. 1 is a perspective view of a tub-covering embodying my invention; Fig. 2 is a transverse sectional view of the device of Fig. 1; Fig. 3 is a fragmentary longitudinal view thereof; Fig. 4 is a perspective view of the covering before application to the tub and inverted to more clearly show the construction thereof; Fig. 5 is a view similar to Fig. 4 but showing another form of covering; Fig. 6 is a cross sectional view, in perspective and on an enlarged scale, showing more clearly the manner in which the covers of Figs. 4 and 5 lie against the interior surface of a tub, and Fig. 7 is a cross sectional view, in perspective, and on an enlarged scale, showing more clearly the manner in which the covers of Figs. 4 and 5 lie against the interior surface of a tub.

Referring now to Figs. 1 to 4, I show a covering 8, preferably of water-proof, acid-proof, crimped or crepe paper, applied to a bath tub 9. It will be understood that cov-

erings of this general form may be also employed for protecting wash-bowls, foot tubs, and similar articles during shipment and installation.

The covering 8 may be of a single sheet of material and is composed of a bottom portion 10, that lies against the bottom of the tub, side portions 11 and end portions 12. The side and end portions or walls of the covering are continuations of the bottom portion 10. The covering is folded as shown more clearly in Fig. 4, and surplus material cut away as indicated at 13 and 14, whereupon the edges 13 and 14 are stitched as indicated and folded flat against the end wall 12 as indicated at 13.

The side walls 11 are provided with flap portions 15 that are adapted to fold down over the outer surface of the side walls of the tub, as shown in Figs. 1 and 2. The flaps 15 are extended longitudinally, somewhat as indicated at 16 in order that the portions 16 will be overlapped by the end flaps as hereinafter explained.

The end walls 12 are provided with flap portions 17 that are adapted to fold down over the ends of the tub as indicated in Figs. 1 and 3. The edges of the flaps 17 are folded in as indicated at 18, so as to provide a double thickness of material that will lie more snugly against the tub and which is not so likely to become torn in handling. When the flaps 17 are folded down over the outer ends of the tub as shown in Fig. 1, the edges 16 of the flaps 15 are thereby covered and protected from being torn.

When the flaps 15 and 17 have been folded into place, adhesive strips 19 and 20 are applied to hold the lowermost edges tightly against the tub. When the tub has reached its destination the plumber may tear the strips 17 and remove the cover from the tub so as to inspect the tub. The covering may then again be placed over the tub so as to protect the same against injury during installation thereof.

In Figs. 5 and 6 I have shown another manner in which the covering may be formed and installed in a tub. In this modification the covering is shown as consisting of a plurality of sheets of material instead of a single sheet. One of the advantages of this form of device resides in the fact that it may sometimes be difficult to secure sheets of such size as to cover large articles. The covering of Fig. 5 is provided with a sepa-

rate bottom sheet 21 to which may be stitched side pieces 22 and 23 that have flap-like extensions corresponding to the flap portions 15 and 16 of Fig. 4. The pieces 22 and 23 are stitched as shown in the drawing. End pieces 24 are stitched to the bottom sheet 21 and to the strips 23. The pieces 24 correspond to portions 17 of Fig. 4 and the complete covering of Fig. 5 is applied to the tub 10 in the same manner as the covering 8 of Fig. 1, being held in place by strips of adhesive material 25.

As a further means of supporting the covers of Figs. 1 and 6, or other forms of covering 15 for a tub, I may provide one or more hoop-like members 26, of metal or wood, that may be inserted in the tub after the cover has been applied, for the purpose of holding the covering snugly against the interior walls of the 20 tub and to assist in retaining the cover against falling out of the tub when the tub is inverted. The hoop 26 may be inserted tightly enough to exert the required frictional engagement with the covering and the wall of 25 the tub.

The covering is preferably made of crimped material, so that a better cushioning effect is produced, and so that it may stretch or give slightly at the corners or bends within the 29 tub, and thereby fit more snugly and will not be so likely to become torn or punctured.

The sewed in bottom may, of course, be employed for covers of various forms other than that of Fig. 5. For example, the side 35 walls of Fig. 5 may be made integral with one another.

Another important feature of my invention resides in the fact that the cover is so formed as to avoid overlapping of the material, or in other words, two thicknesses of material at any point upon the rim of the tub where such rim may be brought into contact with the wall during the "tilting in" process. A single thickness of material will not hold 45 the tub away from the wall a distance sufficient to be objectionable.

In order to effect this object I cut out adjacent corner portions 28 and 29 of the side and end flaps 16 and 17, respectively, as shown 50 in Fig. 4. The point of juncture of the edges 28 and 29 is approximately at the outermost rim of the tub. The cover of Fig. 5 may be similarly cut away at 28 and 29, although

in this form of device there is overlapping of the parts 22—23 but, as above stated, these 55 portions may be made of a single sheet of material.

I claim as my invention:

1. A protective covering for bath tubs and the like, comprising a body portion conforming to the interior of a tub, side flap portions on said body portion extending over the longitudinal edges and the sides of the tub, other flap-like portions extending over the outer end walls of the tub, the end flap portions 60 overlying the vertical edges of the side flaps and having their vertical edges folded inward.

2. A protective covering for bath tubs and the like, comprising a body portion conforming to the interior of a tub, side flap portions 70 on said body portion extending over the longitudinal edges and the sides of the tub, and other flap-like portions extending over the outer end walls of the tub, the vertical edges 75 of some of the flap portions overlying the vertical edges of adjacent flap portions and being folded.

3. A protective covering for bath tubs and the like, comprising a body portion conforming to the interior of a tub, side flap portions 80 on said body portion extending over the longitudinal edges and the sides of the tub, other flap-like portions extending over the outer end walls of the tub, and end flap portions overlying the vertical edges of the side flaps 85 and having their vertical edges folded inward at points exteriorly of the tub and below the rim portion thereof.

4. A bath tub cover comprising a body portion adapted to fit upon the interior bottom 90 portion of a tub, flap portions extending from the longitudinal edges and the ends of such body portion, the said flap portions being secured together at such points adjacent to their contiguous edges as will cause them to 95 form a unitary structure conforming substantially to the body portion of the tub, the lines of attachment of said flap portions to one another, extending for a distance not substantially greater than the height of the tub, but 100 the flaps themselves extending beyond the upper edge of the tub.

In testimony whereof I, the said ROBERT E. HENRY, have hereunto set my hand.

ROBERT E. HENRY.
